Nelson Geertsen, Chicago, Ill., assignor to American Can Company, New York, N. Y., a corporation of New Jersey

Application February 10, 1942, Serial No. 430,298

11 Claims. (Cl. 164—20)

The present invention relates to sheet metal presses and the like and has particular reference to cutting metallic sheets into parts and feeding the parts in opposite directions while stacking them for quick inspection and subsequent handling.

In the can making industry flat blanks from which can bodies are made usually are cut from large sheets. Some can bodies, such as those used for tearing strip cans, require an additional die cutting operation on one edge of each blank to form the tearing strip tongue and its adjacent notch. Such can bodies require manual handling for inspection and stacking after being cut from the sheet and again after the die cutting operation. This requires considerable time and expense for handling the blanks.

The instant invention contemplates saving this time and expense in handling by providing a machine in which double blank strips are divided by a die mechanism that forms the body tongue and notch and in which the blanks after cutting are fed in opposite directions to stackers which receive them in position for inspection and for subsequent handling.

An object therefore of the invention is the provision of a sheet metal press wherein strips of stock are fed from a magazine into a die mechanism which cuts the strip across and along an irregular line of severance that divides the strip into two can body blanks each having a shaped edge that may include a projecting tongue and an adjacent notch, the blanks after cutting being discharged laterally and in opposite directions to stackers which receive the blanks in an arrangement which permits of quick inspection and subsequent handling.

Another object is the provision in such a machine of gauging devices wherein the strips to be cut are gauged and located in the die mechanism from the feeding edge of the strip so that the strip will be properly located in the die mechanism for cutting.

Another object is the provision of such a machine wherein the various moving parts for feeding the strips may be adjusted laterally of the machine so that strips of different sizes may be accommodated in the machine.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a machine embodying the instant invention, with parts broken away;

Fig. 2 is a top plan view of the machine shown in Fig. 1 with the upper portion of the machine broken off and shown in section and with other parts of the machine broken away, the view also showing a plurality of blanks in stacked arrangement in the machine;

10 Fig. 3 is a front elevation of the machine, with parts broken away;

Fig. 4 is a detailed view of a portion of the machine, with parts broken away;

15 Fig. 5 is an enlarged sectional view taken substantially along the line 5—5 in Fig. 1, with parts broken away;

Fig. 6 is a sectional view taken substantially along the broken line 6—6 in Fig. 5, with parts broken away, the view also showing in section a plurality of blanks in the machine;

20 Fig. 7 is an enlarged sectional view taken substantially along the line 7—7 in Fig. 2, with parts broken away, the view also showing a blank in section;

25 Fig. 8 is an enlarged elevation of a detailed portion of the machine as viewed from the back of the machine, with parts broken away;

Fig. 9 is an enlarged sectional detail taken substantially along the line 9—9 in Fig. 2, with parts broken away;

Fig. 10 is a sectional view taken along the line 10—10 in Fig. 9;

Fig. 11 is a sectional detail taken substantially along the line 11—11 in Fig. 5, with parts broken away;

Fig. 12 is an enlarged sectional detail taken substantially along the line 12—12 in Fig. 2, with parts broken away;

40 Fig. 13 is a sectional view taken substantially along the line 13—13 in Fig. 6, with parts broken away;

Fig. 14 is a top plan view of a strip of sheet metal from which can body blanks are produced in the machine;

Fig. 15 is a sectional view taken substantially along the line 15—15 in Fig. 6, with parts broken away; and

Fig. 16 is a sectional detail taken substantially along the line 16—16 in Fig. 2.

As a preferred embodiment of the invention the drawings illustrate a machine in which comparatively long pre-cut metallic strips A (Fig. 14) of tin plate or the like material, are cut along a transverse irregular line B to produce two individual can body blanks C (Fig. 2) having along

the severed edge a projecting tongue D and an adjacent cooperating notch E.

Such a machine primarily includes a conventional punch press section L (Figs. 1 and 2), a strip feed mechanism M, and a pair of continuously moving conveyor stackers N, located one on each side of the feed mechanism. The strips A, in a horizontal position extending across the machine, are fed by the feeding mechanism into the punch press L. Here the strips are divided by being cut across to produce the two separate can body blanks. Immediately after cutting, the blanks are fed transversely of the machine in opposite directions and are received on the stackers N in an overlapping stacked condition, spaced so that they may be readily inspected while on the stackers. The blanks as needed are easily scooped up manually and removed to any suitable place of deposit for subsequent operations.

The operating parts of the punch press L are carried on a conventional punch press frame 21 (Figs. 1 and 2) while the working parts of the feed mechanism M and of the stackers N are carried on a main frame 22 (see also Figs. 5 and 6). One end of the main frame is bolted to the press frame 21 while the other end is supported on legs 23 which, with the press frame, are secured to a base plate 24.

The strips A to be formed into the can body blanks C are retained in a magazine 27 (Figs. 1, 2, 3 and 6) in which the blanks are maintained in stack form by a pair of vertical, spaced and parallel corner angle irons 28 and a plurality of straight vertical magazine bars 29. The angle irons are secured to a pair of side guide rails 31 which extend longitudinally of the machine. The magazine bars 29 are bolted to a cross beam 32 which is secured at its ends to brackets 33 fastened to the main frame 22.

The stack of strips A within the magazine is supported on a plurality of support bars 35 formed on right angle arms 36 which are adjustable transversely of the machine. The bars are secured in position by clamps 37 (Fig. 6) and bolts 38, the bolts being threaded into the outer ends of a pair of spaced and parallel longitudinal slide rails 39. The two slide rails are located one on each side of a centrally disposed stationary support rail 41 which extends longitudinally of the machine and is secured to the main frame 22.

In order to have the magazine 27 adjustable for strips of different lengths, the guide rails 31 and the slide rails 39 are mounted adjacent their ends on T shaped blocks 43. The blocks are located in T slots 44 formed in the main frame 22. The blocks in turn are threaded onto long screws 45. There are four screws in all, two screws having left hand threads for the guide rail 31 and the slide rail 39 on one side of the stationary rail 41, and two screws having right hand threads for the guide rail and the slide rail on the opposite side of the stationary rail 41.

The slide rail blocks 43 are mounted on a reduced diameter section 46 of each of the screws 45, this section having a thread pitch of one-half the thread pitch of the larger diameter sections of the screws. The inner ends of each set of right and left hand screws are formed with a square shank 47 which fits within a sleeve 48 having a square hole therein. In this manner each set of two screws is tied together so that they can rotate as one.

The outer ends of the screws 45 are carried in bearing blocks 49 which fit within the T slot 44 and which are secured to the main frame.

Beyond the bearing blocks each screw carries a sprocket 51 and the two sprockets on each side of the machine are connected by endless chains 52. One of the screws is provided with a square shank 53 for the reception of a wrench or handle.

Hence, when a wrench or handle is applied to the square shank 53 all the screws may be rotated simultaneously. Rotation of the screws in either direction moves the guide rail 31 and the slide rail 39 on one side of the stationary rail 41, toward or away from the guide rail and the slide rail on the opposite side of the stationary rail. In this manner the rails may be drawn nearer each other or may be spread apart to change the length of the magazine 27 to accommodate a particular size of the strip A. In accordance with the pitch of the screw, the guide rails 31 move twice as fast as the slide rails 39 and this keeps the proper relation between the rails as they are shifted to accommodate the strips.

The strips A are fed individually from the bottom of the magazine 27 by first drawing them down toward a feed level or feed line. This drawing down of the strips is effected by a pair of vacuum cups 56 (Figs. 1, 2 and 6). The vacuum cups are mounted on vertical slides 57 carried in long depending bearings 58 bolted to the bottoms of the slide rails 39. There is one cup and one slide for each slide rail and they move with the rail when the latter is shifted to bring it into an adjusted position.

The upper end of each slide 57 extends up through an opening 59 in its rail 39. The lower end of each slide is connected to a flexible pipe 61 which leads to a suitable source of vacuum. This pipe is in communication with a passage way 62 which extends through the slides and which communicates with the cups 56.

The vacuum cups 56 are moved up into engagement with the lowermost strip A in the magazine 27, by a pair of spur gears 65 which mesh with rack teeth 66 formed on the cup slides 57. The gears are mounted on a cross shaft 67 (see also Fig. 3) which extends across the front 45 of the machine and which is carried in bearings 68 formed on the machine leg sections 23. This shaft is rocked periodically by a lever 71 which is mounted on the shaft.

The outer end of the lever 71 is connected by a link 72 to a yoke 73 (see also Figs. 5 and 11) which straddles a spacer sleeve 74 on a shaft 75 which constitutes the main drive shaft of the machine. The yoke carries a cam roller 76 which operates in a cam groove 77 formed in a face cam 78 mounted on the drive shaft adjacent the spacer sleeve. The drive shaft is journaled in a plurality of spaced bearings 81 which are formed in the main frame 22. The ends of the shaft extend beyond the frame and one end carries a driving sprocket 82 which is driven by an endless chain 83. The chain may be driven in any suitable manner.

Thus as the main shaft 75 rotates, it revolves the cam 78 and this reciprocates the link 72 in time with the other moving parts of the machine. Reciprocation of the link rocks the lever 71 and the cross shaft 67 on which it is mounted and this rotates the spur gears 65. The gears in turn move the cup slides 57 through an up stroke 70 and then through a down or return stroke.

On the up stroke the vacuum cups 56 connected to the slides, engage against the lowermost strip A in the magazine 27 as hereinbefore mentioned and thus take hold of the strip by means of the vacuum being drawn on the cups.

On the down stroke of the slides, the cups draw the strip down to the feed line in two places located between the strip support bars 35. The vacuum remains on the cups temporarily to hold the pulled down strip in this position.

While the strip is thus retained in its pulled down condition it is removed from the magazine 27 and advanced along the guide rails 31 and slide rails 39, in a step-by-step movement, for cutting. This removal of the strip and its advancement through the machine is brought about by a plurality of reciprocating feed bars 85 (Figs. 2, 3 and 6) having the usual feed dogs 86 spaced at intervals along their lengths. The drawings show four of these feed bars and they are located two in each slide rails 39 and straddling the vacuum cup slides in the rails, the bars sliding in longitudinal grooves 87 formed in the rails.

The two feed bars 85 in each slide rail 39 are connected together by a spacing block 88 which extends down through an opening 89 formed in the bottom of the rails. The spacing block for each set of feed bars is formed with a depending lug 91 and these two lugs are connected by adjustable links 92 to the upper ends of a pair of spaced actuating arms 93 (see also Fig. 4). The arms are mounted loosely on a cross shaft 95 mounted in bearings 96 formed on the machine legs 23 (see also Fig. 1).

The actuating arms 93 are tied together by an adjusting screw 98 which is carried in a rocker arm 99 keyed to the cross shaft 95. The actuating arms are held in place on the screw by locknuts 101. By adjusting these nuts on the screw, the arms may be moved along the cross shaft to keep them in line with the slide rails 39 when the latter are adjusted for different sizes of strips.

The actuating arms 93 are rocked to reciprocate the feed bars 85 through a forward or feeding stroke and thence through a return stroke, by a crank link 103 (Fig. 6). The outer end of the link is formed with a fork 104 which engages around the rocker arm 99 and the adjusting screw 98. The inner end of the crank link is carried on a crank 105 formed on the main drive shaft 75 (see also Fig. 5). It is this crank that rocks the actuating arms 93 and thus reciprocates the feed bars 85.

On a forward stroke of the feed bars 85 the feed dogs 86 on the outer ends of the bars engage behind the pulled down portions of the lowermost strip A in the magazine 27 and push the strip forward. Simultaneously with this forward movement of the strip, the vacuum is broken and the vacuum cups 56 thereby release their hold on the strip to let it move forward. It is this movement of the feed bars that removes the strip from the magazine.

After removal of a strip A from the magazine it is advanced by the feed bars 85 through the machine in an intermittent or step-by-step movement as hereinbefore mentioned, this being toward the punch press section L. During this advancement of the strip it is held against upward displacement by a plurality of hold-down bars 111 (Figs 2 and 6). These hold-down bars engage against the top surfaces of the strips as they move along the slide rails 39 and the stationary rail 41. Bars 111 are mounted adjustably on a cross shaft 112 so that they may be shifted with the slide rails. The ends of the cross shaft are carried in bearings 113 formed in the brackets 33. The outer edges of the mov-

ing strips are held down by overhanging ledges 114 which extend inwardly from the guide rails 31.

When an advanced strip A arrives at the punch press section L of the machine, it first is located in a predetermined position prior to being cut. The locating of the strip is brought about by a pair of gauge blocks 116 (Figs. 2, 7 and 12) and a pair of gauge fingers 117. Each gauge finger 117 is located adjacent the inner end of the associated feed bar 85 being disposed in a groove 118 formed in a bracket 119 bolted to the inside of the guide rail 31. Each finger is mounted on a pivot pin 121 secured in the bracket and is held under pressure of a flat spring 122 which is secured to the bracket. Only the head of the finger extends above the bracket and in the path of travel of the strips advancing along the feed line.

The gauge blocks 116 are located opposite the gauge fingers 117. These blocks are rectangular in shape and are located in wide grooves 125 formed in brackets 126 secured to the inner ends of the guide rails 31. Each block is movable within its groove 125 under the resistance of a compression spring 127 disposed in a recess 128 in the bracket. The spring is interposed between the bracket and a lug 129 which extends down from the bottom of each gauge block and projects into the recess 128. The gauge blocks are held against upward displacement by cap screws 131 which extend down through slots 132 formed in the blocks. The screws are threaded into the brackets 126.

When the feed bars 85 move through a forward stroke, the last or innermost set of feed dogs 86 carried thereon advances the strip A over the top of the gauge fingers 117 and pushes the leading edge of the strip against the gauge blocks 116. The feed bars and the strip being advanced thereby, push the blocks 116 back against the resistance of their springs 127 until the feed bars come to the end of their stroke. The stroke is sufficient to carry the back edge of the strip past the gauge fingers 117 and accordingly the fingers snap up into position behind the strip as shown in Fig. 7. On the back or return stroke of the feed bars 85, the gauge blocks 116 acting under their compressed springs 127 push the strip back into gauging contact with the fingers 117 as shown in Fig. 7. This locates and holds the strip in position for cutting.

Cutting of the strip is effected by a die mechanism which includes a lower stationary die member 141 (Fig. 2) and an upper movable cooperating punch member 142 (Fig. 5). The die member 141 is bolted to the main frame 22. The punch member 142 is secured in a conventional punch head 143 which vertically is reciprocated in a slideway 144 formed on the press frame 21 (Figs. 1, 3 and 5). The punch head is actuated by a pitman 145 carried on a crank shaft 146 journaled in bearings 147 on the press frame.

The press crank shaft 146 is rotated in time with the other moving parts of the machine by an endless chain 151 which operates over a sprocket 152 mounted on the crank shaft and over a driving sprocket 153 mounted on an auxiliary driving shaft 154 journaled in bearing brackets 155 bolted to the press frame 21. An idler sprocket 156 carried on an arm 157 secured to the bearing brackets keeps the chain 151 taut. The auxiliary drive shaft 154 is rotated from the main drive shaft 75 by way of an endless

chain 159 which operates over sprockets 161, 162 mounted on the respective shafts.

With such a drive connection the crank shaft 146 is rotated continuously and thus reciprocates the punch head 143 through a down or working stroke and thence through an up or return stroke. It is on the down stroke of the head that the punch member 142 cuts through the pre-located strip A on the die member 141 and thus divides the strip into two can body blanks C. Pilot members 165 on the punch head 143 pass into holes 166 in the die member 141 to keep the punch member 142 and the die member in register.

During and immediately following this cutting operation the blanks C are supported on a pair of short table blocks 167, located one on each side of the die member 141. These blocks are secured to the main frame 22. The outer ends of the blanks are supported on table extensions 168 of the guide rails 31. Intermediate their lengths, the blanks are supported on table bars 169 which are secured to the inner ends of the slide rails 39.

Immediately after being cut, the blanks C are discharged laterally and in opposite directions, from the die mechanism. This is to make room for the next incoming strip A. This discharge of the blanks is brought about while the punch head 143 is traveling upwardly through a return stroke and is effected by upper and lower discharge rollers 171, 172 (Figs. 2 and 5) respectively. There are two sets of these rollers, one set being located on each side of the machine adjacent the outer edges of the blanks C.

The lower discharge rollers 172 are mounted on short shafts 173 (see also Fig. 7) which are journaled in bearings 174 formed in the gauge block brackets 126 which, it will be recalled, are bolted to the inner ends of the guide rails 31. These lower rollers are rotated continuously at high speed by sprockets 176 which are mounted on the short shafts 173. The sprockets are rotated by endless chains 177. Each of these chains operate over a pair of idler sprockets 178, 179, an idler sprocket 181 and a driving sprocket 182, the chains being arranged over these sprockets as best shown in Fig. 5. The axis of the sprocket 181 may be shifted.

The idler sprockets 178, 179 of each drive are arranged in spaced relation below the roller sprocket 176 and they are mounted on short shafts 185 carried in bearings 186 formed in the two arms of a pair of inverted T-shaped legs 187 that extend down from each gauge block bracket 126. Each idler sprocket 181 is mounted on a short shaft 188 carried in the lower end of a hanging arm 189 which is mounted on a pivot shaft 191 secured in the main frame 22. The two drive sprockets 182 for the two drives are mounted on two separate spaced and parallel shafts 193 (see also Fig. 6) which are journaled in bearings 194 formed in the main frame.

The two drive sprocket shafts 193 are rotated in unison and in opposite directions by a pair of meshing spur gears 195 which are mounted on the shafts. One of the shafts 193 carries a sprocket 196 (see also Fig. 13) which is rotated by an endless chain 197 that operates over a sprocket 198 mounted on a drive shaft 199 journaled in bearings 201 (see also Figs. 2 and 6) formed in the press frame 21. The outer end of the drive shaft carries a bevel pinion 202 which meshes with and is driven by a bevel gear 203 mounted on the driven shaft 154. It is this

driven shaft and bevel gear and pinion that rotates the gears 195 and through these gears drives the chains 177 that revolves the lower discharge rollers 172 continuously and in opposite directions.

With this manner of drive for the lower discharge rollers 172 and their connection with the drive chains 177, the rollers and the brackets in which they are carried may be shifted transversely of the machine with the guide rails 31 when the latter are adjusted for different sizes of strips A, this shifting taking place without in any way disturbing the adjustment of the driving chains or the sprockets over which they operate. This construction of driving mechanism provides for quick and easy change of the machine parts for different sizes of strips A.

The upper discharge rollers 171 (Figs. 5 and 6) are mounted on long studs 211 carried in roller arms 212 mounted on short pivot shafts 213 disposed in bearings 214 (see also Fig. 2) formed in roller brackets 215 secured to the inner ends of the guide rails 31. The brackets 215 form a connection between the upper discharge rollers 171 and the guide rails 31. When the guide rails are shifted to accommodate different sizes of strips A, the upper rollers move with their brackets.

The outer ends of the upper roller studs 211 carry cam rollers 218 (see Fig. 6) which operate in straight cam grooves 219 (see also Fig. 5) in bar cams 221. There is one of these cams for each upper discharge roller 171 and they are secured to the tops of a pair of vertical slides 222 disposed in slideways 223 (see also Figs. 2 and 8) formed on the back of the main frame 22. The slides are connected by links 225 to levers 226 (see Figs. 1, 5 and 13) which are mounted on pivot shafts 227 carried in bearings 228 formed in the main frame 22. The pivot shafts carry cam arms 229 having cam rollers 231 which operate in cam grooves 232 of barrel cams 233 mounted on the main drive shaft 75.

Hence the rotation of the main drive shaft 75 rotates the cams 233 and rocks the cam levers 229 and their pivot shafts 227. This rocks the levers 226 and thus reciprocates the slides 222 through a down or working stroke and thence through an up or return stroke in time with the other moving parts of the machine. Reciprocation of the slides 222 lowers and raises the bar cams 221 and this shifts the upper discharge rollers 171 toward and away from the lower continuously moving discharge rollers 172.

The normal position of the upper discharge rollers 171 is directly above and in spaced relation to the lower discharge rollers 172 so that a strip A upon being advanced into position for cutting will pass between the rollers and stop directly over the lower rollers. After the strip is cut to form the blanks C, the upper rollers are moved down to engage the blanks and to press them against the lower rollers. It is this pressure on the rotating lower rollers that effects the discharge of the blanks, the lower rollers frictionally engaging the bottoms of the blanks and quickly feeding them outwardly at right angles to their former advancement through the machine and in opposite directions so that one blank will be discharged toward the left as viewed in Figs. 2 and 5 and the other blank toward the right.

The inner ends of the moving blanks C are guided as they are discharged from the die mechanism by guide plates 241 (Figs. 2 and 16) which

are located adjacent the die member 141 and the table blocks 167. There are two of these guide plates 241 and they are secured to guide blocks 242 having depending tongues 243 which slide in grooves 244 formed in the top of the table blocks 167.

The guide blocks 242 are retained against displacement from the table blocks 167 by bolts 245 which extend through slots 246 in the guide blocks, the bolts being threaded into the table blocks. These guide blocks are backed up by spring barrels 247 carried in bores 248 formed in the press frame 21. A light spring 249 located in each spring barrel keeps the guide plates 241 extended to guide the blanks properly during discharge while rendering the guide plates yieldable in case it becomes necessary.

Provision is made to permit the passage of the blanks C being discharged, past the guide rails 31. These guide rails extend up to the die mechanism and guide the strip A to be cut, into proper endwise relation to the die mechanism. Such guiding is done by a vertical slide plate 255 (Figs. 2, 5 and 7) which is located at the inner end of each of the guide rails 31. This plate is flush with the inside surfaces of the rails to continue the guiding of the strips.

These slide plates 255 are disposed in slideways formed in the guide rails 31 and in the discharge roller bracket 126 so that the plates will shift with the guide rails when the latter are adjusted for different sizes of strips. Each plate is formed with a horizontal slot 256 which is large enough to permit a blank C to pass through endwise. The plates are connected to lever arms 257 which are mounted on the upper roller arm shaft 213.

The normal position of the slides 255 is such as to bring their slots 256 above the path of travel of a strip A moving into position in the die mechanism for cutting. Hence the plates guide the ends of the strip while it is being located, as hereinbefore mentioned. After the strip is cut and while the upper discharge rollers are moving down to press the blank against the lower rollers, the lever arms 257 depress the guide plates to bring their slots 256 into alignment with the ends of the blanks. In this position of the slide plates, the blanks being discharged pass through the slots.

The blanks C when discharged by the rollers 171, 172 travel with considerable momentum and upon passing through the slots 256 in the slide plates 255 they slide along a pair of runways 261 from which they fall onto a pair of continuously moving stacker belts 262. There is one of these belts located at each side of the machine. The blanks are guided into position onto the belts by vertical side guides 263, 264 and an end stop plate 265. Guides 263 serve to carry the other parts 264, 265 and are secured to outwardly projecting extensions 267 (one on each side) of the main frame 22. Each plate 265 stops the outward travel of its blank and the guide members inside insure that it will fall horizontally onto its belt in a predetermined position.

Each stacker belt 262 (Fig. 1) operates over a pair of spaced pulleys 271 located one adjacent the discharge end of the machine and the other adjacent the front end. The pulley adjacent the discharge end is mounted on a short idler shaft 272 carried in bearing brackets 273 bolted to the frame extensions 267. The forward pulley 271 is mounted on a stacker drive shaft 275 which extends across the front of the ma-

chine and carries the forward pulleys on both sides of the machine. This shaft is carried in bearing brackets 276 which are secured to the frame extensions 267.

5 The stacker drive shaft 275 is rotated slowly in an intermittent or step-by-step manner by a free-wheeling device 281 (Figs. 2, 9 and 10) which includes a clutch member 282 which is keyed to the shaft. The clutch member is formed

10 with a plurality of spaced wedge shaped recesses 283 in each of which is located a gripping roller 284. This clutch member and its rollers are disposed in a surrounding housing 285 having a cover plate 286 secured to one side thereof to retain the clutch in place. The housing is formed on a lever arm 287 which surrounds the drive shaft 275 and which is connected by a link 288 (see Figs. 3 and 6) to a rocker arm 289 mounted on the rock shaft 95.

20 Hence the rocking motion of the rock shaft 95 is transmitted by way of the rocker arm 289, link 288, and lever arm 287 to the clutch housing 285. This rocks the housing in a counter-clockwise direction and thence in a reverse direction, as viewed in Fig. 10. When the housing rocks in a counter-clockwise direction it wedges the gripping rollers 284 between it and the clutch

25 282 and thereby rotates the latter through a partial rotation. When the housing rocks in the reverse direction, the gripping rollers 284 fall back in their recess 283 and hence free the clutch from the housing thereby permitting the clutch to remain stationary on the reverse stroke. This is a usual free-wheeling construction.

30 35 In this manner the stacker drive shaft 275 is rotated intermittently in one direction and in time with the other moving parts of the machine and the stacker belts 262 are thus moved forward toward the front of the machine in time

40 45 with the discharge of the blanks from the die mechanism. This timing is such that for every blank discharged, the belts move forward a distance less than the width of the blanks so that the received blanks will overlap each other on the belt, as best shown in Fig. 2. In this stacked relation the blanks may be readily inspected by the operator of the machine as they travel with the belts. The blanks preferably are removed manually by scooping them up from the belts

50 55 although the belts may be extended if desired to carry the blanks to any suitable place of deposit.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for cutting sheet metal strips, the combination of a die mechanism having upper and lower cooperating cutting instrumentalities for cutting a strip across to produce two blanks, two continuously rotating rollers located one on each side of said die mechanism and adjacent said blanks, and an idler roller opposite each of said rotating rollers, said idler rollers being movable toward said rotating rollers for squeezing blanks therebetween to discharge the blanks endwise from said die mechanism and in opposite directions.
2. In a machine for cutting sheet metal strips,

the combination of a die mechanism having upper and lower cooperating cutting instrumentalities for cutting a strip across to produce two blanks, two continuously rotating rollers located one on each side of said die mechanism and adjacent its cut blank, an idler roller opposite each of said rotating rollers and movable toward its associated rotating roller for squeezing the blank therebetween for discharging the two blanks endwise from said die mechanism and in opposite directions, and means for moving said idler rollers in synchronism with the operation of said die mechanism to discharge the blanks at the proper time.

3. In a machine for cutting sheet metal strips, the combination of a die mechanism having upper and lower cooperating cutting instrumentalities for cutting a strip across to produce two blanks, two continuously rotating rollers located one on each side of said die mechanism and adjacent opposite ends of the blanks, means for driving said rotating rollers, devices for shifting said rotating rollers laterally of said die mechanism while maintaining driving connection with said driving means to accommodate blanks of different lengths, and an idler roller located opposite each of said rotating rollers which is movable toward its associated rotating rollers for squeezing a blank therebetween to discharge the blanks endwise from said die mechanism and in opposite directions.

4. In a machine for cutting sheet metal strips, the combination of a die mechanism having upper and lower cooperating cutting instrumentalities for cutting a strip across to produce two blanks, two continuously rotating rollers located one on each side of said die mechanism and adjacent said blanks, a driving sprocket for each of said rotating rollers, a plurality of idler sprockets adjacent each rotating roller, an idler roller disposed opposite each of said rotating rollers, an endless chain operating over said sprockets for driving each of said rotating rollers, some of said sprockets being movable with said rollers relative to said die mechanism to adjust the rollers for blanks of different lengths, and means for moving said idler rollers toward their associated rotating rollers to squeeze blanks therebetween to discharge them in opposite directions.

5. In a machine for cutting sheet metal strips, the combination of a die mechanism for cutting a strip across to produce two blanks, feeding devices for feeding the strips into said die mechanism in timed order, guide rails for guiding the strips into said die mechanism, and blank discharge means for removing the cut blanks laterally from said die mechanism and in opposite directions, said guide rails being movable toward each other and said discharge means being adjustable therewith to accommodate strips of different lengths.

6. In a machine for cutting sheet metal strips, the combination of a die mechanism for cutting a strip across to produce two blanks, guide rails for guiding and endwise locating a strip in position relative to said die mechanism, blank discharge means adjacent said die mechanism for removing cut blanks laterally so that the two blanks from each strip will be discharged simultaneously from opposite sides of said die mechanism, a movable guide plate located in each of said guide rails adjacent said die mechanism and

having an opening therein to allow a discharged blank to pass through, and means for shifting said guide plate in time with said die mechanism first to bring said plate opening into register with the cut blank as it is discharged and then to shift it out of register for locating the strip prior to cutting.

7. In a machine for cutting sheet metal strips, the combination of a die mechanism for cutting a strip across to produce two blanks, reciprocating feed bars having spring held feed dogs for advancing strips into said die mechanism in timed order, gauge fingers adjacent said die mechanism being compressible by a strip entering into said die mechanism and snapping up behind the strip edge as the strip comes therein, yieldable gauge devices opposite said gauge fingers for returning the advanced strip into engagement with said snapped-up fingers to locate the strip relative to the die mechanism, and blank discharge means adjacent said die mechanism for removing cut blanks laterally therefrom and in opposite directions.

8. In a machine for cutting sheet metal strips, the combination of a die mechanism for cutting a strip across to produce two blanks, blank discharge means located adjacent said die mechanism and on opposite sides thereof for removing cut blanks laterally therefrom so that the two blanks from each strip will be discharged from opposite sides of said die mechanism, and a conveyor located on each side of said die mechanism for receiving the blanks discharged therefrom.

9. In a machine for cutting sheet metal strips, the combination of a die mechanism for cutting a strip across to produce two blanks, blank discharge means located adjacent said die mechanism and on opposite sides thereof for removing cut blanks laterally therefrom said that the two blanks from each strip will be discharged from opposite sides of said die mechanism, a conveyor located on each side of said die mechanism for receiving the blanks discharged therefrom, and means for actuating said conveyor in synchronism with the operation of said die mechanism so that the blanks will be received on said conveyor in an overlapped and stacked relation to facilitate inspection of the blanks.

10. In a machine for cutting sheet metal strips, the combination of a die mechanism for transversely severing a metal strip to produce two blanks therefrom, duplicate blank discharge means located adjacent said die mechanism and on opposite sides thereof, said discharge means being ineffective for discharge of a blank during the blank cutting operation, and actuating means operable in time with the movement of said die mechanism for rendering said blank discharge means effective to remove the severed blanks in opposite directions from the die mechanism.

11. In a machine for cutting sheet metal strips, the combination of a die mechanism having upper and lower cooperating cutting instrumentalities for cutting a strip transversely to produce two blanks, two cooperating pairs of discharge rollers located on opposite sides of said die mechanism, and means for bringing each pair of rollers into position to discharge the cut blanks laterally and in opposite directions following said cutting operation.

NELSON GEERTSEN.
